UNITED STATES PATENT OFFICE.

JOHN AUGUST GUSTAVSON, OF CHICAGO, ILLINOIS.

DOOR-KNOB.

SPECIFICATION forming part of Letters Patent No. 433,464, dated August 5, 1890.

Application filed December 12, 1887. Serial No. 257,623. (No model.)

To all whom it may concern:

Be it known that I, JOHN AUGUST GUSTAVSON, a resident of Chicago, Cook county, and State of Illinois, and a citizen of Sweden, 5 have invented certain Improvements in Door-Knobs, of which the following is a full description.

My invention consists of an improvement in the manner of constructing door-knobs applicable to any form of lock or latch that is operated by a knob, so as to wholly prevent rattling and lost motion.

In the accompanying drawings, Figure 1 represents a longitudinal sectional view of 15 two slightly-differing forms of my improved knob as attached to a door G. Fig. 2 shows a transverse view of the body of the knob with the head removed, and Fig. 3 represents one method of securing the head to the body 20 of the knob.

The rose or plate C, which may be fastened to the door G either by the screws c² or by claws or barbs cast as a part of said plate, is provided with a tubular stem c and c', within 25 which the rectangular spindle D revolves freely. The ends of the spindle D are fitted into corresponding rectangular holes in the body A and A' of the knobs 1 and 2 at d', by which means a rotary motion is imparted to 30 it. The parts are retained in place by the adjustment of a nut E upon the threaded ends d² of the spindle D, and to prevent this nut from working loose a washer F is placed beneath it. The spindle D is threaded for a 35 sufficient distance at each end to permit of the use of the knob upon doors of varying thickness.

The body A of the knob 1 is fitted nicely upon the stem c and seated within a suitable 40 recess in the rose C, so that it has a long lateral bearing upon the stem c and a firm transverse bearing upon the rose C. The body A' of the knob 2 has its transverse bearing at the outer end and its lateral bearing upon 45 the sides of the stem c'.

The head B of the knobs 1 and 2 may be of any desirable form, care being taken to provide for ample space for the end of the stem D in case of the use of the knob upon a thin 50 door, and it may be attached to the body A and A' in a variety of methods. The most

desirable method of attachment is illustrated in Fig. 3, in which the head B serves the purpose merely of a face or front, the body A constituting the knob proper, and being the 55 portion grasped by the hand in practical use. It will be seen that very little strain will come upon the head B in this method of construction, and hence it will be retained securely in its place if the joint b² is made a close fit, 60 and two or more small flat springs, as a², are attached to head B, each being provided with the rounded lug a³ at its loose end to engage in a suitable groove in the inner wall of the body A when the head is adjusted. The head 65 can be readily removed by inserting a chisel or other similar tool at the joint b². Should the head be attached in manner similar to that shown in Fig. 1, by means of the screws b, it will be found advisable to make the 70 body A and A' with small longitudinal ridges and the head B with corresponding grooves, so as to prevent the head from turning and to relieve the screws b from the strain that would otherwise fall upon them. Fig. 2 shows 75 these ridges a' upon the inner wall of the body A, the head to be adjusted within the body, and not upon it, as in Fig. 1.

It will be seen that in attaching my improved knob to a door the usual unpleasant 80 lateral play is wholly prevented by the proper adjustment of the nuts E, while the stem c and c' entirely prevents all transverse motion, and the knob is limited to the simple rotary motion desired. 85

I claim—

1. A spindle D, having its ends threaded and supplied with the nuts E, in combination with the knob 1, consisting of the body A, having a lateral bearing upon and external 90 to a fixed tubular stem, the head B, and the rose C, having a tubular stem, substantially as and for the purposes described.

2. In a door-knob, the body A, with the head B adjusted thereto by the joint b', and the 95 spring a² and lug a³, adapted to secure said head and body together, substantially as shown and described.

JOHN AUGUST GUSTAVSON.
